PANEL FOR A FURNITURE DOOR

Herman W. Bernard, High Point, N.C., assignor to Casard Furniture Manufacturing Corporation, High Point, N.C., a corporation of North Carolina

Filed Oct. 16, 1968, Ser. No. 14,015

Term of patent 14 years

Int. Cl. D6—01

U.S. Cl. D33—1

FIG. 2

FIG. 1

FIG. 1 is a front elevational view of a panel for a furniture door illustrating my design;

FIG. 2 is a transverse sectional view taken along line 2—2 of FIG. 1; and

FIG. 3 is a left end view of FIG. 1.

I claim:

The ornamental design for a panel for a furniture door, as shown.
